UNITED STATES PATENT OFFICE.

FRANK GROSSI, OF PROVIDENCE, RHODE ISLAND.

CLOCK AND TIME CONTROLLED SWITCH FOR ELECTRIC LIGHTS.

Application filed January 27, 1927. Serial No. 164,047.

This invention relates to time control switches for electric lights and its general object is to provide a switch of this character for automatically controlling a parking lamp 5 of a vehicle, so that the lamp will be illuminated and extinguished at predetermined times.

A further object of the invention is to provide a combined vehicle clock and switch 10 for the dual purpose of indicating the time and also to control a circuit to an electric lamp carried by the vehicle; the switch being actuated by mechanism in the clock casing and said mechanism being capable of being manually set so that the switch is actuated at predetermined times for controlling the lamp accordingly.

Another object of the invention is to provide a time controlled switch that is efficient 20 in operation, simple in construction, and inexpensive to manufacture.

This invention also consists in certain other features of construction and in the combination and arrangement of the several parts, 25 to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front elevation of the device forming the subject matter of the present invention.

Figure 2 is a sectional view taken on line 2-2 of Figure 1 and looking in the direction of the arrows.

Figure 3 is a view similar to Figure 1 with the dial of the clock removed and showing parts in section.

Figure 4 is a top plan view of the device in applied position to an instrument board of a vehicle and showing parts broken away and 45 in section.

Figure 5 is a sectional view taken on line 5-5 of Figure 3.

Figure 6 is a sectional view taken on line 6-6 of Figure 5.

Figure 7 is a detail view of one of the spring disks.

Figure 8 is a similar view of the spring actuated gear which is associated with the disk as shown in Figure 7.

Figure 9 is a sectional view taken approximately on line 9-9 of Figure 3.

Figure 10 is a perspective view of the switch actuating member.

Figure 11 is a diagrammatic view of the device and its circuit applied to an automobile.

Referring to the drawings in detail the numeral 1 indicates the clock casing which is provided with the usual frame 2 for receiving the clock train as indicated in dot and dash lines as shown in Figure 3 and this frame also has arranged therein and formed with a sleeve keyed to the hour hand arbor, a gear 3 which meshes with similar gears 4 and 5 disposed upon opposite sides thereof and 70 mounted for rotation on stub shafts 6 and 7 which includes part of the setting mechanism of the switch actuating mechanism which will be presently described. The stub shafts 6 and 7 are each provided with knurled finger 75 pieces 8 which are secured to the projecting ends thereof as best shown in Figure 9, whereby these shafts can be rotated as will be readily apparent, and fixed to the shaft 6 is a dog 9 while the shaft 7 has fixed thereto 80 a dog 10. Secured to the stub shafts 6 and 7 are ratchets 11 which are provided with pawls 12 secured to the gears 4 and 5.

Pivottally mounted in the frame 2 in a manner whereby their lower ends are arranged 85 in the path of the rotation of the dogs 9 and 10 are arms 13 and 14 respectively. The arm 13 is provided with a rounded upper end which terminates in a substantially V-shaped 90 detent 15, while the arm 14 is of substantially bell crank shape in configuration and also terminates in a substantially V-shaped detent. The lower ends of these arms 13 and 14 are held in the path of the dogs 9 and 10 through the instrumentality of coil springs 16. These 95 detents 15 cooperate with substantially V-shaped notches arranged in the periphery of small disks 18 and 19 respectively. The disk 19 is integrally formed with one end of a sleeve 20 which is mounted for rotation on a 100 stub shaft 21, and formed on the opposite end of said sleeve 20 is a gear 29 which is fixed to a large disk 23 forming one side wall of a housing for a spring 24. The opposite side 105 wall of the housing is also in the nature of a disk 25 which has formed therewith a hub 26 also having connection with the spring 24 and stub shaft 21 as best shown in Figure 5 of the drawings. This last mentioned disk is provided with tongues 27 arranged circumferentially on one side thereof as shown in Figure 7, and which cooperates with elongated sub-

stantially rectangular shaped recesses 28 provided in a gear 22 which has formed therewith the small disk 18. The stub shaft 21 is provided with a finger piece 30 whereby the spring can be wound thereon for a purpose which will be presently described. Arranged upon opposite sides of the stub shaft 21 are arbors 31 and 32 which have secured thereto pinions 33 and 34. The pinion 33 meshes with the gear 22, while the pinion 34 meshes with the gear 29 as best shown in Figure 4 of the drawings. Each of these arbors 31 and 32 have also secured thereto cam members 35 and 36 respectively which cooperate with studs 37 laterally extending from the substantial U-shaped arm 38 formed on the switch operating member as best shown in Figure 10. The body portion of this arm 38 is provided with slots 39 through which pass screw bolts 40 for securing said arm for slidable movement to one side portion of the frame 2. The outer end of the arm terminates in a right angled bent portion 41 which has secured thereto through the instrumentality of a screw bolt 42 an elongated insulating block 43 which as shown is circular in cross section and provided with a groove 44 formed in its upper surface. This insulating block extends into a laterally disposed casing 45, fixed to the clock casing as shown in Figure 3 and which has insulating material 46 arranged therein. The insulating material 46 is provided with a circular bore to accommodate the block 43 as well as a metallic piece 47 of circular cross section which is fixed to the block for movement therewith as will be readily apparent. The insulating material is further provided with aligned vertical bores through which pass binding posts 48 having their inner ends terminating in heads 49 curved to follow the curvature of the bore of the insulating material and arranged in spaced relation for passage of the metallic piece in a manner whereby said piece will engage the heads for closing a circuit. Arranged in the aligned bores of the insulating material 46 are coil springs 50 which retain the binding posts in their innermost positions for engagement with the metallic piece or the insulating block as the case may be which will be readily apparent. The head 49 of the upper binding post 48 is provided with a depending rib 51 disposed to be received in the groove 44 or a similar groove 52 which registers with the groove 44 as best shown in Figure 10 of the drawings.

The clock is provided with the usual dial 53 through which passes the arbor for the hour hand as well as the arbor for the minute hand as suggested in Figure 1 of the drawings, and arranged on the dial 53 are dials 54 and 55 through which passes the shafts 6 and 7 respectively. Fixed to the projecting ends of these last mentioned arbors are hands associated with the numerals on the dials 54

and 55 which are provided with the words "Off" and "On" respectively as shown. Fixed to the hour and minute arbors respectively are the appropriate hands for cooperation with the numerals of the dial 53.

The circuit for the switch is disclosed in Figure 11, and extending from one of the binding posts 48 is a conductor 56 having electrical connection with a parking lamp 57 in the present instance, and also electrically connected to the parking lamp is the opposite conductor 58 which is connected to a source of electrical energy 59 from which extends a conductor 60 connected to a conductor 61 having its ends electrically connected to the opposite binding post and to one side of a manually control switch 62, while the opposite side is electrically connected to the conductor 56 through the instrumentality of a conductor 63.

From the above description and disclosure in the drawings, it will be obvious that I have provided a time controlled switch that is adapted to operate at predetermined times for illuminating and extinguishing lamps, and in the present instance the switch is shown in circuit with a parking lamp of an automobile as shown in Figure 11, and if it is desired to have the switch illuminated at a certain time, the shaft 7 is rotated for positioning the hand thereof with respect to the numeral on the dial 55, it depending of course what time it is desired to illuminate the parking lamp. For instance, if it is desired to illuminate the parking lamp at four o'clock, the switch 62 is closed and the hand of the arbor 7 is set at four o'clock as shown in Figure 1, and if it is desired to extinguish the parking lamp at seven o'clock the hand of the arbor 6 is set at seven o'clock as shown. Of course, the spring 24 is wound about its shaft 21 through the medium of the finger piece 30. When the gear 3 rotates the gear 5 of the shaft 7, to arrange the dog 10 for engagement with the arm 13, the dog will move the detent 15 out of the V-shape notch of the disk 18 and therefore release the same so that the spring 24 will rotate the gear 22 which will in turn rotate the gear 33 and cause the cam member 35 to engage the adjacent stud 37 and slide the arm 38 so as to position the metallic piece 47 in contacting engagement with the binding posts 48 as shown in Figure 3 of the drawings and thereby closing the circuit to the parking lamp 57. The switch will remain closed until seven o'clock at which time the gear 3 will have moved the gear 4 in a position so that the dog 9 will engage the arm 14 for moving the detent 15 thereof out of the V-shape notch of the disk 19 so that the spring 24 will at that time rotate the gear 29 which meshes with the gear 34 secured to the arbor 32 and this arbor will cause the cam member 36 to engage the adjacent stud 37 of the arm 38 and posi-

tion the metallic piece out of engagement with the heads of the binding post and arrange the insulating block between the heads 49 and thereby open the circuit to the parking lamp. From the above description, it

will be further seen that the spring will operate either of the gears 22 or 29 alternately as each are secured to the spring as set forth.

The detents prevent movement of the disks

18 and 19 until the detents are entirely removed from the V-shaped notches of these disks by the dogs 9 and 10 which are arranged so as not to entirely remove the detents until the dogs snap off the ends of the 15 arms 13 and 14. The detents allow only one revolution of the disks 18 and 19, as the springs 16 for the arms 13 and 14 force the detents back into the notches after such revolution.

20 The gears 33 and 34 are rotated by the arbors 31 and 32 which have secured thereto the cam members 35 and 36 as set forth. The cam members are provided with curved and straight surfaces as best shown in Figure 3 25 of the drawings, and are arranged whereby the surfaces will be disposed in opposed relation with respect to each other, with the result when one cam member has moved the switch arm by the engagement of the curved surface thereof with its stud 37, the straight surface of the other cam member is arranged so as to allow its stud to pass toward the curved surface of this last mentioned cam member so that this stud will be arranged in 30 the path of the curved surface of its cam member for reversing the movement of the switch arm when the last mentioned cam member is moved by its arbor.

It is thought from the foregoing description 40 that the advantages and novel features of my invention will be readily apparent.

I desire it to be understood that I may make changes in the construction and in the combination and arrangement of the several parts, provided that such changes fall 45 within the scope of the appended claims.

What I claim is:

1. In a device of the character described, a 50 clock, a time controlled switch associated with said clock and including a casing laterally disposed and secured to the casing of the clock, an arm mounted for reciprocation in the clock casing, insulating material arranged in said first mentioned casing and being provided with a bore, an insulating block of circular cross section secured on said arm and arranged in said bore, a metallic piece secured to the free end of said insulating block for movement therewith, a pair of 55 spaced binding posts arranged in alignment in bores formed in said insulating material, heads on said posts and being arranged in the path of the insulating block and metallic piece respectively, means on one of said heads 60 and being engageable in grooves formed in

the metallic piece and said insulating block, and mechanism operated by the clock mechanism for reciprocating said arm at predetermined times.

2. The combination with a clock and its 70 casing, of a time controlled switch comprising a casing laterally secured to the clock casing, insulating material arranged in said first mentioned casing and being provided with a rounded bore, a frame included in the clock mechanism, a substantially U-shaped arm provided with slots, means secured to said frame and receiving said arm for slidable movement thereon, studs extending from said arm, cam members cooperating with said 75 studs for moving the arm, mechanism for operating the cam members at predetermined times, binding posts arranged in aligned bores formed in the insulating material, heads formed on the inner ends of said 80 binding posts, an insulating block secured to said arm, a metallic piece secured to the outer end of said insulating block which together with said metallic piece is capable of being disposed between the heads upon movement of the arm accordingly, and resilient means for retaining said heads in contacting engagement with the insulating block and metallic piece respectively.

3. In a time controlled switch, a casing, 85 an arm mounted for reciprocation, an insulating block secured to one end of said arm and movable in said casing, a metallic piece secured to the free end of said insulating block and movable with the latter, studs extending laterally from said arm, means engageable with said studs at predetermined times for reciprocating said arm accordingly, and spring pressed headed binding posts arranged in the path of the insulating block and 90 metallic piece respectively.

4. A time controlled switch of the character described comprising a casing, spaced contact means arranged in said casing, a contact member slidably mounted in said casing and engageable with said contact means, means for operating said contact member and including a substantially U-shaped arm provided with slots arranged 100 therein, means passing through said slots in a manner for mounting said arm for reciprocation, means for reciprocating said arm and including cam members, studs extending from the arm and being engageable by the cam members, means for operating said cam members and including disks provided with notches, means having detents associated with said notches, means controlled by a clock mechanism and including means engageable 110 with the detent means for releasing the detents from the notches at predetermined times and setting means for the releasing 120 means.

In testimony whereof I affix my signature.
FRANK GROSSI.
